UNITED STATES PATENT OFFICE

JOHN E. SUMPTER, OF MINNEAPOLIS, MINNESOTA, ASSIGNEE TO DELTA-STAR ELECTRIC COMPANY, OF CHICAGO, ILLINOIS, A CORPORATION OF ILLINOIS

EXTERNAL EXPULSION FUSE PLUG

Application filed October 1, 1924. Serial No. 740,995.

My invention relates to external expulsion fuse plugs wherein it is desired to provide a fuse plug for high tension lines for use on regular cut-outs for closing transformer banks or lines.

The present cut-out fuse plugs will not stand more than two or three blow outs of the fuse before the heat and electric reaction has destroyed the utility of the same, so that 10 a new cut out fuse plug is required. These are usually made of porcelain and if they should blow in an electric storm due to a lightning discharge or the load is increased beyond a determined amount, then the fuse plug may be blown out onto the ground and naturally it would be destroyed. This old 15 type of fuse holder is known as plug cut outs, wherein the fuse wire extends over the top and into the body of the contact housing.

20 My invention provides a device whereby the blowing of the fuse is entirely outside of the body of the cut out housing and more particularly because it is designed to provide handle means whereby the operator can insert the plug into the housing in a manner so that it is practically impossible for him to become injured if the same should blow out, while he is inserting it. The old style of plug cuts outs has no design for protection 25 to the operator and just as like as not it will blow out while he is inserting it, in which case the arc and force of the blowing of the fuse is dangerous to the operator's face and hands.

30 My plug is so designed that the operator can insert it into the cut out without any danger whatsoever to the operator or without the use of special tongs for replacing the same as are now used with the present cut out plugs; and this replacing of my plug can take place while the line is live and without any danger whatsoever as to the blowing of the fuse.

35 A feature of the invention resides in the skirting of the lower end of the plug to form a recess and permit the exposure of the fuse and opening of the fuse chamber so that the blowing of the fuse will be directed straight downward out of the end of the fuse plug.

40 It is also a feature to provide a protecting edge about the lower end of the plug so that

the operator will not place his hand underneath the same and endeavor to force the plug into the housing. This is provided by serrated, pointed surfaces, or in any other suitable manner.

45 My fuse plug is adapted to be made in two half portions so that it can readily be taken apart if desired, or of a solid nature, having a fuse receiving tube extending therethrough in a manner so that the open end of the fuse tube is at the bottom of the plug and the fuse can be readily inserted therein by opening the upper end of the fuse plug and attaching the fuse to the screw cap which closes 50 the upper end of the fuse tube or opening.

55 My invention also includes a cut out housing and fuse plug designed to provide a central web portion which separates the contacting blades of the fuse plug so that during the insertion of the plug the insulating 60 web will prevent any arcing across the terminals. This means of construction entirely separates the terminals so as to provide a protective means between the terminals and a guiding member for the plug, so that the 65 plug can be hingedly connected and snapped into locking position with the cut out housing. This form of construction firmly holds 70 the fuse plug in operative position.

75 The invention includes other features and designs which provide a new and desirable construction and these will be more clearly set forth in the following specification and claims.

80 In the drawings forming part of this specification:

85 Figure 1 is a side elevation of the cut out housing showing my fuse plug attached thereto.

90 Figure 2 illustrates a similar view showing a portion of the housing and fuse plug in section.

95 Figure 3 is a bottom view of the cut out housing.

100 Figure 4 is a plan view of my fuse plug showing the upper end thereof.

Figure 5 is a bottom view of the same.

Figure 6 is an enlarged side illustration showing one half of my fuse plug where the

same is made in separable halves and illustrating the first receiving tube in section.

Figure 7 is a perspective view of my fuse plug ready for use.

5 Figure 8 is a side elevation of an alternative form of my fuse plug and housing.

Figure 9 is a central cross section of the construction illustrated in Figure 8.

10 Figure 10 is a bottom view of the housing of this construction.

Figure 11 is a top view of my fuse plug illustrated in Figure 8.

Figure 12 is a side elevation of my fuse plug as of 12-12 of Figure 8.

15 Figure 13 is a section on the line 13-13 of Figure 9.

20 My fuse plug A is provided with a top 10 and a bottom portion 11 which form the ends of the body or handle portion 12 designed to be easily gripped in the hand of the operator so that the fuse plug A can be inserted into the cut out housing B.

25 The cut out housing B is made of porcelain or other suitable insulating material and is provided with the usual openings for receiving the line wires C on either side thereof, which are connected within the housing in the ordinary well known manner. Figure 3 illustrates a bottom view of the housing 30 illustrating the connections for the line wires therein. The housing B is provided with a central recess 13 which is of a circular nature having angular channel like recesses 14 of the same depth connecting with the circular portion 13 on either side thereof.

35 My expulsion fuse plug is provided with a lug member 15 of a similar shape to the recess 13, excepting of a less than a complete circle in cross section and the lug 15 is formed with a key member 16 which is adapted to fit into the channel openings 14. The fuse plug A can be inserted in any position, held so that the key 16 will fit into either of the channels 14, so that it is reversible for insertion 40 into the housing. The plug A is provided with connecting blades 17 and 18 which are adapted to form contacts with the spring connectors 19 in the housing B when the plug is inserted therein. The blade 17 is connected with and formed integral to the tubular member 20, positioned within the upper portion of the plug A and in which the connecting cap screw 21 is threaded. This cap screw 21 closes

45 the upper end of the fuse tube 22 which is positioned and extends through the body 12 of the handle A and opens into the recess 23 formed in the lower end of the handle. The recess 23 is provided with a downwardly extending skirt 24 about the same so as to provide the necessary depth to the recess 23. The fuse tube 22 can be made of any suitable heat resisting material and where the fuse plug A is formed in a single piece of insulating 50 material, the same is provided with an open-

ing 25 extending through the same which is adapted to receive the fuse wire 26.

55 The fuse wire 26 is connected to the cap plug 21 by the screw 27 or in any other suitable manner at the upper end of the plug A 70 and extends across in the opening 23 to the metallic or conducting member 28, being secured thereto by the screw 29. The conducting member 28 extends through the handle or body portion 12 and is integrally secured 75 to the blade 18 at the upper end of the fuse plug A. In this manner my expulsion fuse plug is provided with a means for receiving a fuse wire 26 with the wire extending downward through the opening 25 and providing 80 an open end 30 into the chamber 23 from the fuse opening 25, so that if the fuse 26 should blow out when the fuse plug A is being inserted into the housing B the force of the blowing of the fuse will be external and will 85 blow out through the opening 30, forcing the fuse plug A up against the housing instead of having a tendency to blow it out of the housing, as is the case in fuse plugs heretofore used. This is an important feature of 90 my invention. The cap screw 21 firmly closes the upper end of the opening 25 and prevents any possible chance of the fuse blowing up into the housing.

95 The skirt 24 protects the operator so that my fuse plug A can be easily held and inserted into the housing B without practically any danger to the operator, whether it is being inserted while the line is live or by reason of any short circuits.

100 The lower end 11 of my fuse plug A is provided with a serrated, sharp, pointed edge which provides a means of protection against the operator placing his hand over the bottom of the fuse plug A to force it into the housing B. This serrated surface can be formed in any suitable manner to carry out the principle of my invention.

105 Where the fuse plug A is formed in two half portions, namely, 31 and 32, suitable holding screws 33 of ordinary construction are provided to hold the parts together. Obviously, the fuse plug A can be formed of a single part, such as bakelite or other insulating material with the opening 25 formed 110 therein and the connecting member 28 cast or otherwise inserted within the handle portion 12 when the same is made.

115 It is quite evident that my fuse plug is of material importance to the operator and also to the user of such devices, for the reason that it will have a tendency to hold itself tighter within the housing if the fuse blows and the explosion in the blowing of the fuse is of an explosive nature, with the force of the blowing being directly downward out of the skirt 24, so as to provide the external expulsion fuse plug, rather than having the fuse blow out up in the recess 13 and channels 14 as is the case of the old type of fuse plugs.

There is no possible chance for the old type of fuse plugs to blow otherwise, because the fuse extends across the web member which is adapted to be inserted into the opening 13 and the channels 14. My external expulsion fuse plug has proven very efficient in tests and operation and accomplishes a result which is most desirable in the protection of the operator and in eliminating the use of tongs or other special means for inserting the same, to say nothing of the saving by reason of the fact that my plug does not blow out onto the ground and break or injure the cut out housing by the intense heat from the blowing of the fuse and the arc caused thereby within the housing. The cut out housing is not heated at all, by the use of my plug, but rather the blowing of the fuse takes place in the handle of the plug and the force and effect of the same is in a downward, external direction rather than within the housing, as has proven so detrimental to the present forms of plugs and cut out housing.

In the drawings in Figures 8 to 13 inclusive, I have illustrated an alternative formation of my fuse plug, together with a cut out housing wherein the fuse plug D which is of the same general construction as the fuse plug A, is hingedly connected by means of the hook 35, which engages in the loop 36 on the back of the housing E, while the spring snap 37 on the front of the housing connects the fuse plug D in operative position to the housing E.

In this construction the fuse plug D is formed with an upwardly projecting, centrally positioned lug member 38, which is formed integral with the body of the plug D or handle portion 39 and provides an insulating member which is adapted to separate the contacts of the housing E. A central recess 40, formed in the housing is adapted to receive the plug 38, which is curved on either side so that the plug D can be attached by engaging the hook within the loop 36 and drawing the plug toward the snap 37, so that the same will engage the housing E. In this way the fuse plug D is snapped into contact position with the housing E.

The plug D is formed with contacting blades 41 and 42 which are adapted to engage in the spring clips 43, positioned within the housing E. The blades 41 and 42 are similar to the blades 17 and 18 of the plug A and form the self-same function in closing the contacts of the cut out housing.

Plug D is provided with a fuse wire 26 which is housed within the handle 39 of the plug D in the same manner as is illustrated for the construction of the plug A. The recess 23 in the bottom of the plug D permits the connection of the fuse wire 26 across the bottom of the same and the opening 25 extending through the handle 39, which is

open at the lower end in the same manner as the plug A, is provided with the opening 30 which permits the force of the blowing of the fuse 26 to be outward, directly through the bottom of the fuse plug D.

In this construction the cap screw 21 engages beneath one of the web members 44, which forms a shoulder against which the same rests when the fuse plug D is in operating position. Thus the webs 44 take the force of the blowing of the fuse to some extent by reason of the contact of the cap screw 21 with one of the webs 44, when the plug is in operative position.

The operation and use of the plug D is of the self-same function as of the plug A so that an external expulsion plug is provided, which protects the operator, prevents the plug from being blown off when the fuse blows out and provides an inexpensive, practical fuse plug for cut outs for high tension lines, which is very practical and of a desirable nature.

In accordance with the patent statutes I have described the principles of my invention, illustrating the best embodiment thereof, but I desire to have it understood that the invention can be carried out by other means and applied to uses other than those above set forth within the scope of the following claims:

I claim:

1. An external expulsion fuse plug, including a handle member, a fuse receiving passage extending through said handle member, said plug having in the bottom thereof an opening communicating with said fuse passage to permit the force of the blowing of the fuse out of the bottom thereof, and a conductor to which one end of the fuse is attached extending through said plug adjacent said fuse passage and a second conductor leading to said fuse passage to which the other end of the fuse is attached to complete the connecting circuit for said plug, both conductors being adapted to make contact with the contacts in a cut out housing.

2. A fuse plug for cut out housings for closing transformer lines, including a separable handle member and accessible fuse receiving means within said handle member positioned in a manner to cause the external expulsion of the force of the blowing of the fuse out of the bottom of said handle member for the purposes specified.

3. A fuse plug for a cut out for transformer banks and lines, including a cut out housing, a guide member adapted to extend into the cut out housing, contact members adapted to engage the contacting clips within said housing and means projecting outside of said cut out housing adapted to contain a fuse replaceably, whereby the blowing of the fuse and the force and effect thereof is entire-

ly without and away from the cut out housing.

4. A fuse plug for high tension cut outs, including a separable handle member adapted to be positioned in a manner to extend from the bottom of the cut out and replaceable fuse attaching means readily accessible within said handle positioned in a manner to permit the fuse to blow out of the bottom of said handle.

5. A fuse plug including a handle, electric contact members projecting from one end of said handle, means for receiving a fuse within said handle in a manner to insulate the same therein and means adapted to permit the blowing of the fuse out of the handle and away from the same for the purposes specified.

6. A fuse plug including a handle member formed of insulating material, means for holding said fuse plug in contact with a cut out housing and a fuse having the major portion thereof replaceably positioned within and protected by said fuse plug, and fuse supporting means including a cap screw adapted to be positioned adjacent said cut out housing and an open end in said fuse plug from which the end of said fuse projects to permit the blowing of the fuse into the open atmosphere, away from the cut out housing.

7. A fuse plug for a cut out high tension housing, including means for supporting a fuse in a manner to cause the fuse to blow out into the open atmosphere, the force of the blowing of the fuse being adapted to tend to force the plug toward the housing to prevent the dropping of the fuse plug upon blowing of the fuse.

8. A fuse plug including a handle member formed of insulating material, a guide shank extending from said handle and formed integral therewith, a key formed on said shank adapted to fit the channel portion formed in a cut out housing in a manner to permit the fuse plug to be inserted from either side thereof, electrical contact members supported by said handle and means for supporting an electrical fuse within said handle in a manner so that the blowing of the fuse will be out of the handle and remote from the cut out housing.

9. A fuse plug including a handle member formed of insulating material, electrical contacts extending into said handle, a guiding portion projecting from said fuse plug handle in a manner to form a guide for the fuse plug in connecting the same to a cut out housing, said guiding member of said handle forming an insulating means adapted to separate the contact members of the fuse plug from each other and from the coating contact members of the cut out housing to prevent arcing across the contacts and fuse supporting means within said handle whereby the blowing of the fuse is entirely in the

handle and remote from the cut out housing.

10. A fuse plug for high tension cut out housing, including a handle member adapted to support a fuse in a manner to cause the fuse to blow out of said handle, a recess formed in said handle having a depending skirt thereabout, out of which the force of the blowing of the fuse takes place, and a serrated edge about said skirt tending to prevent the operator from placing his hand on said skirt to force said plug into the cut out housing.

11. A fuse plug including means for supporting a fuse therewithin, means for closing the fuse opening adjacent the contact side, said fuse plug having an opening in the opposite side thereof through which the fuse supported therein extends, a skirt extending about said opening and protective means formed on said skirt tending to prevent the operator from placing his hand against the same to force the fuse plug into a cut out housing.

12. A fuse plug including means adapted to replaceably support a fuse therein, means for closing the contact side of the fuse plug to prevent the force and effect of the blowing of the fuse toward the contact side thereof, to protect the contacts of the plug against the effect of the blowing of the fuse and to cause the plug to be more firmly forced into contact to prevent dropping of the fuse plug, and a recess in the side of the fuse plug exposing a portion of the fuse in the outer atmosphere.

13. A fuse plug for high tension cut outs including a handle member formed of insulating material, contact blades extending from said handle means for connecting one of said blades with a fuse, a passageway extending through said handle for the fuse, a member extending adjacent said fuse passageway adapted to be connected to the other of said contact blades and a recess in said handle whereby one end of said fuse can be connected and extend across in said recess to contact with said member extending through said handle adjacent said fuse passageway, said recess in said handle permitting the fuse to blow into the open atmosphere.

14. A fuse switch, comprising a socket member having contacts, a removable hollow plug receivable within the socket member, provided with a hollow handle extension adapted to communicate with the interior of the plug, contacts on the plug, complementary to the contacts in the socket member, a fuse cartridge electrically connected with one of the contacts on the plug, and a fusible element having electrical connection with the cartridge and the other contact on the plug.

15. A fuse switch, comprising a socket having spaced contacts, a hollow member

comprising a plug at one end and a handle at the other, the handle projecting outwardly from the socket member, contacts on the hollow member complementary to the contacts in the socket, a fusible member, and a fuse cartridge, said cartridge being in electrical connection with one of the contacts on the hollow member, the hollow member having its free end open to permit gases to escape when the fusible member is fused.
